US00D633417S

(12) **United States Design Patent**
Najarro

(10) **Patent No.:** US D633,417 S
(45) **Date of Patent:** ** Mar. 1, 2011

(54) **UNITARY TOWING HOOK**

(75) Inventor: **Marco A. Najarro**, San Jose, CA (US)

(73) Assignee: **Donna Medved**, San Jose, CA (US)

(**) Term: **14 Years**

(21) Appl. No.: **29/336,903**

(22) Filed: **May 12, 2009**

FIG. 1 is a perspective view of a unitary towing hook in accordance with my design.

FIG. 2 is a forward end view of the design shown in FIG. 1.

FIG. 3 is a rearward end view of the design shown in FIG. 1.

FIG. 4 is a right side view of the design shown in FIG. 1.

FIG. 5 is a left side view of the design shown in FIG. 1.

FIG. 6 is a top view of the design shown in FIG. 1; and,

FIG. 7 is a bottom view of the design shown in FIG. 1.

The broken line showing of a spring in FIG. 6 forms no part of the claimed design.
